UNITED STATES PATENT OFFICE.

LOUIS WOJIDKOW, OF BROOKLYN, NEW YORK.

DESIGN FOR A STAND FOR TEA-KETTLES.

SPECIFICATION forming part of Design No. 27,941, dated December 7, 1897.

Application filed October 20, 1897. Serial No. 655,857. Term of patent 3½ years.

To all whom it may concern:

Be it known that I, LOUIS WOJIDKOW, a citizen of the United States, residing at Brooklyn, in the county of Kings and State of New York, have invented and produced a new and original Design for a Stand for Tea-Kettles, of which the following is a specification, reference being had to the accompanying drawings, forming part thereof.

10 Figure 1 is a perspective side elevation of a stand for tea-kettles, showing my new design; and Fig. 2 is a sectional top view of the same.

15 As shown in the drawings, the leading or material feature of my design consists of an oval or loop shaped ornament, edged by a series of beads, so as to form a beaded border, said loop-shaped ornament being arranged between the uprights of the supports.

20 A indicates the base of the stand, which is supported by means of claw-shaped feet B. The base A has a scalloped and beaded rim, C

indicating the scallops, and C' the beads which edge the scallops.

D indicates the supports which rise from 25 and are inclined outwardly from the base A, each support being formed with a pair of uprights d d', between which, at the upper parts of the same, is arranged a beaded oval E, which is connected at its upper part by means 30 of S-shaped connecting-pieces e with the upper ends of the uprights d d'.

Having described my invention, what I claim as new, and desire to secure by Letters Patent, is—

35 The design for a stand for tea-kettles, substantially as herein shown and described.

In testimony that I claim the foregoing as my invention I have signed my name in presence of two subscribing witnesses.

LOUIS WOJIDKOW.
